UNITED STATES PATENT OFFICE

2,591,123

WIRE-Straightening FIXTURE

Svend G. Blumensaadt, Beachwood Village, Ohio,
assignor to The Universal Wire Spring Company, Cleveland, Ohio, a corporation of Ohio

Original application September 2, 1947, Serial No.
771,592. Divided and this application December 22, 1947, Serial No. 793,271

3 Claims. (Cl. 140—147)

1

This is a divisional application of my co-pending application Serial No. 771,592, filed September 2, 1947, for "Method and Apparatus for Making Wire Springs from Sinuous Wire Strips" and this invention relates in general to wire straightening fixtures and more particularly to specific wire straightening fixtures designed to straighten the ends of sinuously corrugated wire spring members prior to reshaping these ends to attachment means.

The primary object of the invention is the provision of a wire straightening fixture for straightening the curved end portions of sinuously corrugated wire spring members, the fixture embodying shiftable locating and holding means for locating and holding a wire spring member in proper position, and shiftable straightening means for straightening one of the curved end portions of such wire spring member to extend laterally from the wire spring member.

Another object of the invention is the provision of a wire straightening fixture for straightening the curved end portions of sinuously corrugated wire spring members, the fixture embodying shiftable locating and holding means for locating and holding a wire spring member in proper position, and shiftable straightening means rectangularly related to the locating and holding means for straightening one of the curved end portions of such wire spring member to extend laterally from the wire spring member.

A further object of the invention is the provision of a wire straightening fixture for straightening the curved end portions of sinuously corrugated wire spring members, the fixture embodying shiftable locating and holding means and pivotally supported, shiftable straightening means shiftable in substantially rectangular relation to the longitudinal axis of the wire spring member, the straightening means effecting straightening by wiping action on the wire of a curved end portion of a wire spring member and controlling angular relationship of the straightened wire to the axis of the wire member by predetermined rotatable movement of the wire straightening means on its pivotal support.

Additional objects and novel features of construction, combinations and relations of parts by which the objects in view have been attained, will appear and are set forth in detail in the course of the following specification.

The drawings accompanying and forming part of the specification illustrate a certain practical embodiment of the invention, but it will be apparent as the specification proceeds that the

2

structure may be modified and changed in various ways without departure from the true spirit and broad scope of the invention.

In the drawings:

Fig. 1 is a fragmentary plan view of a sinuously corrugated wire spring member having a curved end portion.

Fig. 2 is a view similar to Fig. 1 with the curved end portion of the wire spring member straightened to extend laterally from the wire spring member.

Fig. 3 is a plan view of a wire straightening fixture constructed in accordance with the invention.

Fig. 4 is a front view of the wire straightening fixture shown in Fig. 3.

Fig. 5 is a cross-sectional view through Fig. 4, the section being taken on line 5—5 of said figure.

Fig. 6 is a sectional view on line 6—6 of Fig. 5; and

Fig. 7 is a side view of the wire straightening fixture shown in Fig. 3.

Referring now more in detail to the exemplified form of the invention shown in the drawings, the wire straightening fixture 2 disclosed therein and designed to be attached to and operated by a punch press, not shown, embodies a housing 3, with two lower housing members 4 and 5 and an upper housing member 6, lower housing members 4 and 5 being mounted on a base plate 7 which, as shown, may be secured to the bed plate 8 of a punch press by screw members 9 and upper housing member 6 is attached to lower housing member 5 by set screws 10. The housing 3 has journaled in bushings 11 a shaft 12 which supports two spur gears 14 and 15 meshing with rack bars 16 and 17, respectively, spur gear 14 meshing with the horizontally arranged rack bar 16 and spur gear 15 meshing with the vertically arranged rack bar 17. The horizontally arranged rack bar 16 is slidably mounted in housing 3 and held in proper working position by an angle bracket 18 and a plate 19. The horizontally arranged rack bar 16 supports a forming block 20 which is pivotally secured to said rack by means of a screw bolt 21. This forming block mounts a roller 22 and when shifted with rack bar 16 in the direction of arrow 23 has such roller cooperating with a cam member 24 to control the pivotal movement of the forming block. The roller 22 is yieldingly forced into contact with the cam surface of the cam member 24 by a torsion spring 25 which is mounted on the upper part of the screw bolt 21. When shifted, forming block 20

slidably engages the looped end 26 of a sinuously

corrugated wire 27 and straightens the wire of the looped end with a wiping action while simultaneously forcing such wire into engagement with the cam surface of a stationary block 28.

To properly locate a sinuously corrugated member and hold same during wire straightening operations, fixture 2 embodies two vertically, shiftably supported locators 29 and 30 and a stationary locator 31. Locator 29 embodies a plunger 32 with a cone-shaped, circular lower portion 33, which plunger is vertically, shiftably mounted in the upper housing member 6. The plunger 32 is forced upwardly by a compression spring 34 and shifted downwardly by a lever 35 mounted on a shaft 36 which is journaled in upper housing member 6. This shaft mounts a gear 37 which meshes a gear 38 on a shaft 39 journaled in upper housing 6 and this latter shaft is oscillated by a cam mechanism 40 embodying a lever 41 which supports a follower 42. The follower cooperates with a cam 43 on a third shaft 44 journaled in housing 60 and rotated by a second vertically arranged rack bar 45. Thus shaft 44 mounts a gear 46 meshing with the rack bar 45 so that vertical shifting of this rack bar effects rotation of shaft 44 and cam 43, oscillation of shaft 39 by cam mechanism 40 and vertical shifting of plunger 32 by lever 35, the compression spring 34 effecting continuous working contact between follower 42 and cam 43 of the cam mechanism. Locator 30 is mounted to move jointly with locator 29 and consists of a flat bar having at its lower end an inverted V-shaped slot 47 to provide the locator with two prongs 48, 48' adapted to guide the wire of a sinuously corrugated wire into the desired position and hold same firmly during wire straightening operations. Proper location of a wire spring member in the straightening fixture is additionally effected by the stationary locator 31 which is shaped to fit the curvature of one of the loops 49 of the corrugated wire. This stationary locator is positioned to align the respective loop of the corrugated wire with locator 30 and for such purpose is slotted at 50 to permit locator 30 to properly hold the wire of the loop when engaging locator 31.

The thus described wire straightening fixture when mounted for actuation on a punch press has its base plate 1 secured to the bed plate 8 of such punch press by the set screws 9 and has its vertically shiftable rack bars 17 and 45 attached to the ram by means of a plate 51 secured to the ram and adjustably connected to vertical rack bars 17 and 45 by means of stud bolts 52, 53. Actuation of the punch press causes downward shifting of the rack bars 17 and 45 which successively effect locating and holding of a sinuously corrugated wire member by locators 29, 30 and 31 and thereafter straightening of the end loop of such wire member by wiping action of the forming block 20 shifted together with the horizontal rack bar 16 and pivotally guided by the cam surface of cam member 24. After wire straightening operations, the wire spring member is released by a spring-pressed ejector plate 54 vertically, shiftably supported on pins 55 encircled by compression springs 56 which rest against ejector plate 54 and are seated in recesses 57 in lower housing member 5.

Having thus described my invention, what I claim is:

1. A wire straightening fixture for straightening the loop of a corrugated wire strip comprising a frame including a supporting surface, vertically shiftable and stationary locating and holding members including locators arranged to be shifted at a right angle to said supporting surface and adapted to axially locate and rigidly hold looped portions of a sinuously corrugated wire strip supported in a flat position on said supporting surface, a slide on said frame arranged to be shifted parallel to the supporting surface at a right angle to the longitudinal axis of a corrugated wire strip located on said surface by said locating and holding members, a stationary wire forming block, a second wire forming block pivotally supported by said slide to swing in the plane of such corrugated wire strip, stationary cam means on said frame adapted to pivotally shift the pivotally supported forming block and effect in cooperation with the stationary wire forming block by wiping action straightening of the end loop of such corrugated wire strip in its plane when the slide is shifted at a right angle toward the corrugated wire strip, and actuating means coupling said stationary locating and holding members with said slide including cam means for successive actuation of said shiftable locating and holding members and said slide.

2. A wire straightening fixture as described in claim 1, wherein said actuating means include means for shifting said locating and holding means, a cam arrangement controlling the operation of said shifting means, a second means for shifting said slide, and a single rotary means coupled with both said cam arrangement and said second shifting means for effecting successive operation of said locating and holding means and said slide.

3. A wire straightening fixture as described in claim 1, wherein the slide supporting the forming block includes a rack bar forming part of said actuating means for joint operation of said vertically shiftable locating and holding means and said shiftable wire straightening forming block.

SVEND G. BLUMENSAADT.
